UNITED STATES PATENT OFFICE.

CHARLES HOFMAN, OF ROCHESTER, NEW YORK, ASSIGNOR, BY MESNE ASSIGNMENTS,
TO BERTHA VIRGINIA HOFMAN, OF ROCHESTER, NEW YORK.

FOLDABLE SHIPPING-BOX.

1,254,692.

Specification of Letters Patent. Patented Jan. 29, 1918.

Application filed May 24, 1916. Serial No. 99,500.

To all whom it may concern:

Be it known that I, CHARLES HOFMAN, of Rochester, in the county of Monroe and State of New York, have invented certain new and useful Improvements in Foldable Shipping-Boxes; and I do hereby declare the following to be a full, clear, and exact description of the same, reference being had to the accompanying drawings, forming a part of this specification, and to the reference-numerals marked thereon.

My invention has for its purpose to construct a foldable packing or shipping box from a single blank of material, such as cardboard, heavy paper, or other flexible fibrous substance, and is designed to afford a structure which can be more or less economically manufactured and furnishes a rigid, strong and durable container susceptible of being readily packed and fulfills all the requirements of a box of this general class. To these and other ends the invention consists in certain improvements and combinations of parts, all as will be hereinafter more fully described, the novel features being pointed out in the claims at the end of the specification.

In the drawings:

Figure 1 is a perspective view of the blank from which the box is formed;

Fig. 2 is a sectional view showing the blank partially assembled and collapsed;

Fig. 3 is a transverse sectional view of the box when assembled;

Fig. 4 is a sectional view on line 4^a—4^a of Fig. 3, looking in the direction indicated;

Fig. 5 is a vertical sectional view on line 5^a—5^a of Fig. 3, and

Fig. 6 is a perspective view showing the box assembled for filling.

Similar reference numerals in the several figures indicate the same parts.

The invention may be carried out in different ways other than that about to be described, but for the purposes of illustration, I have shown a preferred embodiment for which there is employed a blank, which comprises two body portions each consisting of a central section 1 and side sections 2, the latter being adapted to overlap one another in the completed box, as illustrated in Fig. 4. The body portions are disposed on opposite sides of an end 3, which is connected thereto by walls 4 that are adapted to fold against the inner surfaces of the walls of

the body portions, as indicated in Fig. 3, so that the end 3 may be inset with reference to the ends of the body portions. The walls 4 are secured against the walls of the body portions in any desirable manner, as by staples, rivets or the like. The end 3 has connected to its free edges extensions, one of which comprises an inner wall 5 and an outer wall 6, while the other comprises an inner wall 7 and outer wall 8. The wall 8 is adapted to be located interiorly of the adjacent wall of the body portion, as shown in Fig. 5, for attachment thereto, affording a bracing and stiffening means, while the wall 6 is adapted to be positioned exteriorly of the body portion and to be secured after the box is filled, insetting of the end 3 being permitted in each instance by the inner walls 5 and 7.

A second end 9 is similarly connected with the adjacent body portion and is provided with extensions at its free edges, including inner walls 10, 11 and 12, respectively, and outer walls 13, 14 and 15 respectively. The walls 14 and 15 are wider than the wall 13, as shown, and are adapted to lie adjacent the inner surfaces of the walls of the body portion, to which they are attached by securing devices that may be used for the purpose.

In assembling the structure, the parts are secured together in the manner shown in Fig. 6, with the upper flaps 2 of the body portions and the walls 6 and 13 of the extensions open, and after the box is packed, the side sections 2 are brought downwardly into overlapping relation and the walls 6 and 13 are then secured by nailing, riveting or otherwise.

I claim as my invention:

1. A blank for a foldable shipping box, comprising body portions with sections of one body portion adapted to overlap corresponding sections of the other body portion, an end located between said body portions, walls connecting the end and body portions, and adapted to lie adjacent to walls of the body portions when the box is folded to afford an inset end, extensions at the free edges of said end adapted to lie adjacent to the walls of the body when the box is folded, a second end connected to one of the body portions by a wall adapted to lie adjacent to a wall of the body when the box is folded, and extensions carried by the free

edges of the second end and adapted to be located adjacent to the walls of the body when the blank is folded, the said end extensions acting to hold the aforesaid overlapping sections of the body portions together.

2. A blank for a foldable shipping box comprising body portions with sections of one body portion adapted to overlap corresponding sections of the other body portion, an end, a wall connecting said end and

body portion, and extensions carried by the free edges of the end and adapted to lie adjacent to the walls of the body when the blank is folded, and acting to hold the aforesaid overlapping sections of the body portions together. 15

CHARLES HOFMAN.
